VERTICAL FLAME OIL BURNER

Jack Berger, Laurelton, N. Y.

Application June 18, 1954, Serial No. 437,689

2 Claims. (Cl. 158—28)

The present invention relates to oil burners.

More particularly, the present invention relates to an arrangement of oil burner parts in the interior of an air tube of an oil burner, and more especially in the interior of the air tube of a vertical flame oil burner.

In conventional oil burner installations there is a blower which blows air along a horizontally extending air tube to an outlet where the air mixes with atomized fuel, and the mixture is then burned. In the so called vertical flame oil burner, the flame extends vertically from the horizontally extending air tube so that the air as well as the fuel flowing substantially horizontally along the interior of the air tube turn through a right angle before being burned. This turning to produce the vertical flame creates certain difficulties in the maintenance of the parts. Thus, the ignition and nozzle assemble must be capable of directing the fuel-air mixture upwardly while the components of the mixture are received horizontally from the air tube, and as a result this nozzle and ignition assembly in the known constructions cannot be removed for maintenance purposes unless the entire air tube is removed from the furnace or the like. Such removal of the entire burner is very undesirable because of the time and work involved. Furthermore, in vertical flame oil burners of known constructions there is no means for controlling the air supplied while the installation remains operatively connected to the furnace.

One of the objects of the present invention is to overcome the above drawbacks by providing a vertical flame oil burner which is capable of having its nozzle and ignition assemble removed from and inserted in to the interior of the air tube without in any way disturbing the latter.

Another object of the present invention is to provide an exceedingly simple arrangement for enabling the nozzle and ignition assembly as well as certain other parts connected thereto to be quickly and easily removed from and reinserted into the oil burner tube.

A further object of the present invention is to provide a means adjustable from the exterior of the air tube while the latter is mounted in its operative position for controlling the air flowing to the space surrounding the nozzle where this air becomes mixed with the atomized fuel.

An additional object of the present invention is to provide an arrangement where this air control means is removable from the interior of the air tube together with other parts connected to the nozzle and ignition assembly and together with the latter assembly.

It is also an object of the present invention to provide a structure capable of accomplishing all of the above objects and at the same time being made up of simple and ruggedly constructed parts which are very reliable in operation and which have a long life.

With the above objects in view the present invention mainly consists of a vertical flame oil burner which includes an elongated air tube and a flame control means

2

located at one end portion of the tube for controlling a flame which is propagated transversely to the length of the tube. A nozzle and ignition assembly is located next to the flame control means for producing a flame to be controlled thereby, this assembly being removably mounted in the air tube at the end portion thereof where the flame control means is located. A fuel supply means is connected to the nozzle and ignition assembly and extends therefrom along the interior of the air tube toward an opposite end thereof, this fuel supply means being removably connected to the air tube and adapted to be connected with a source of fuel located outside of the air tube. A current supply means also is connected to the nozzle and ignition assembly and extends therefrom along the interior of the air tube toward an end portion thereof distant from the flame guiding means, and this current supply means also is removably connected to the air tube. Furthermore, an air control means is connected to the nozzle and ignition assembly for controlling the flow of air from the interior of the air tube through the assembly, this air control means extending from the assembly through the interior of the air tube toward its end portion distant from the flame control means and through a wall portion of the air tube to a point at the exterior thereof. Finally, a closure means is located at the end portion of the air tube distant from the flame control means for closing and opening the air tube and for providing upon being opened a passage through which the nozzle and ignition assembly together with the air control means, fuel supply means, and current supply means may be removed from and inserted into the air tube without disturbing the latter.

The novel features which are considered as characteristic for the invention are set forth in particular in the appended claims. The invention itself, however, both as to its construction and its method of operation, together with additional objects and advantage thereof, will be best understood from the following description of specific embodiments when read in connection with the accompanying drawings, in which:

Fig. 1 is a partly sectional view taken in a vertical plane longitudinally extending through an air tube of an oil burner and illustrating the arrangement of the present invention in the interior of the air tube;

Fig. 2 is a partly sectional plan view taken along the line 2—2 of Fig. 1 in the direction of the arrows;

Fig. 3 is a side view of the parts which are removable from and insertable into the air tube of the oil burner;

Fig. 4 is a fragmentary view taken in the direction of arrow A of Fig. 3 and showing the construction of the parts at the bottom side of the nozzle and ignition assembly.

Referring now to the drawings, Fig. 1 shows an air tube 10 provided with air by a blower 11 of known construction and driven by a motor or the like in a known way. The air tube 10 may be a one piece construction or may include several tube sections joined in end to end relation. Fig. 1 shows adjustable supports 12 engaging the underside of the air tube 10 for adjusting the elevation and inclination thereof.

The left end of the air tube 10, as viewed in Fig. 1, is provided with an end wall 13 formed with an opening 14, and a cover plate 15 is pivotally connected, for example, by a screw 16 to end wall 13 so that this cover plate 15 may be turned to and from a position closing the opening 14. The cover plate 15 may be fixed in its closing position by a removable screw 17. As will be apparent from the discussion which follows, plate 15 and opening 14 form a closure means which provides a passage through which various parts may be inserted into

and removed from the interior of air tube 10 without disturbing the latter, this opening 14 of course being large enough to permit the parts to pass therethrough.

The end portion of tube 10 distant from wall 13 thereof is formed by a vase casting 18 of a vertical flame burner, this casting 18 having an open top. A plurality of channel members 19 are fixed to and extend upwardly from the open top of casting 18, and these channel members 19 are distributed about casting 18. A flame control means is located on top of the casting 18 for turning movement thereon. This flame control means takes the form of a cover 20 formed at its center with an opening 21 and carrying about this opening an upwardly flaring flame guiding member 22 of known construction. A plate 23 is fixed to the underside of cover 20 and is provided about its periphery and at its top face with a plurality of upwardly directed projections 24 which form between themselves passages extending tangentially to the nozzle which supplies the atomized fuel so that air in the interior of tube 10 flows through these passages to produce an efficient flame, in a known manner. The cover 20 carries at its outer periphery a plurality of annularly spaced projections 25 each of which is shorter than the distance between channel members 19 so that these projections 25 may be moved downwardly between the channel members 19 until cover 20 engages the top face of casting 18, and then the parts 20, 22 and 23 are turned as a unit to locate the projections 25 within the channels 19 so that in this way the cover 20, plate 23 and member 22, all of which form a flame control means, are turnable for flame adjusting purposes on the casting 18 but cannot be removed therefrom until the projections 25 are again located between the channel members 19.

In accordance with the present invention, a nozzle and ignition assembly 26 engages the underside of plate 23 and extends partly into an opening in the center of the plate 23. This nozzle and ignition assembly includes a housing 27 in which the nozzle 28, of known construction, is located and in which the ignition electrodes 29 are located. The nozzle 28 is held against the bottom wall of housing 27 by a screw 30 extending through an opening in its bottom wall and engaging the nozzle 28. The left wall of housing 27, as viewed in Fig. 1, is formed with an opening through which an oil supply duct 31 passes, this oil supply duct 31 being connected to the nozzle 28 for supplying oil thereto in a known way.

The electrodes 29 also extend through the left wall of housing 27, and at the exterior of this left wall the tube 31 and electrodes 29 are clamped together by a clamp 32 which may, for example, take the form of a pair of resilient metal strips one of which engages the bottom side of tube 31 as well as the bottom sides of electrodes 29 and the other of which extends across the tops of the electrodes 29, these strips being connected together by bolts 33 and nuts 34 located between the electrodes 29 and oil duct 31.

Although the housing 27 may be constructed in different ways, it is preferred to form this housing from a bottom section 27b and a top section 27a, these sections having overlying lugs which are interconnected by fastening members extending through aligned openings in these lugs, for example. Openings are drilled through the wall of the lower section 27b to accommodate the oil duct 31 and the electrodes 29.

As is apparent from Figs. 1 and 2, the top of housing 27 is open so that the oil spray passes upwardly through the flame control means, and the parts 20, 22 and 23 may be turned as a unit with respect to housing 27 to adjust the flame in a known way. The housing 27 is resiliently maintained in engagement with the plate 23 by a leaf spring 35 engaging the inner bottom surface of the air tube 10 and being connected to the

underside of the housing 27 in the particular example illustrated.

As is apparent particularly from Fig. 2, the oil duct 31 extends toward opening 14 and is joined adjacent to opening 14 with a coupling 36 having its interior in connection with the interior of duct 31 and passing through an opening in the side wall of air tube 10 where this coupling 36 is then joined to a line 37 leading from an oil pump. Parts 36 and 37 are removably connected to each other through any suitable known threaded members so that in this way parts 36 and 37 can be separated and part 36 can be moved inwardly away from the side wall of air tube 10.

The electrodes 29 are respectively connected to a pair of electrically conductive lines 38, which are suitably insulated and which also extend along the interior of tube 10 toward the opening 14 thereof, these lines 38 being connected at their ends distant from electrodes 29 to an ignition transformer so mounted, for example, on the side of air tube 10.

In accordance with the present invention a means is provided for controlling the flow of air through the housing 27. In order to accomplish this result the bottom wall of housing 27 is formed with one or more openings 39 distributed about the screw 30. This screw 30 in addition to maintaining the nozzle in position on the bottom wall of housing 27 turnably supports a plate 40 having openings which can be aligned with the openings 39 in one angular position of plate 40, and this position corresponds to the maximum air flow through the housing 27.

A rod 41 is turnably connected at its right end, as viewed in Fig. 1, to the underside of plate 40 and extends along the interior of tube 10 to a point where the rod 41 is bent in substantially a right angle and extends through a slot 43 in the side wall of tube 10. A nut is threaded adjacent the free end of rod 41 next to the inner surface of tube 10, and a second nut 42 threadedly engages the portion of rod 41 extending to the exterior of the tube 10. The slot 43 through which the rod 41 extends extends horizontally parallel to the axis of tube 10, and because of the small size of the openings 39 as well as the openings in plate 40, the slot 43 can be relatively short in order to provide sufficient movement for rod 41 to adjust the extent to which openings 39 are uncovered by the plate 40.

As is evident from Fig. 4, the rod 41 is located to one side of the screw 30. In all positions of the rod 41 the slot 43 is covered by a washer 44 which is large enough to accomplish this result, so that in the adjusted position of rod 41 the slot 43 is closed. Thus, by loosening nut 42 it is possible to shift rod 41 from the exterior of the air tube to adjust the flow of air through the housing 27, and then the nut 42 is tightened to maintain the rod 41 in its adjusted position. The nut 42 may also be removed from rod 41 so that the latter can be separated from the side wall of tube 10.

The above described structure operates in a known way. That is, the air flowing along the interior of tube 10 moves about the housing 27 through the tangential passages formed by plate 23 to swirl tangentially about the spray of oil and to mix therewith, and also the air flowing upwardly through the interior of housing 27 mixes with the oil and is burned, the oil being supplied through duct 31 to the nozzle 28. When the apparatus is started a spark moves across the space between electrodes 29 adjacent to the tip of the nozzle in a known way.

Assuming now that for some reason it is necessary to make adjustments to the nozzle and ignition assembly or to perform other maintenance thereon, with the structure of the invention it is only necessary to uncover opening 14 by moving plate 15 away therefrom and to then disconnect wires 38, rod 41 and coupling 36 from the air tube. Then by grasping the rod 41 and duct 31 and pressing downwardly thereon the spring 35 is bent and the housing 27 moves downwardly from plate 23 and the operator may then simply remove these parts through

70
75

the opening 14. The parts are reinserted and placed in their operative positions through the reverse of the above operations. A suitable elongated tool may be used by the operator to compress spring 35 to facilitate the insertion of the upper housing portion 27a into the central opening of plate 23. The control rod 41 may be adjusted from the exterior of the air tube 10 without removing any parts, as was described above, so as to adjust the flow of air through the housing 27.

It will be understood that each of the elements described above, or two or more together, may also find a useful application in other types of oil burners differing from the types described above.

Without further analysis, the foregoing will so fully reveal the gist of the present invention that others can 15 by applying current knowledge readily adapt it for various applications.

What is claimed as new and desired to be secured by Letters Patent is:

1. In a vertical flame oil burner, in combination, an 20 elongated air tube; a first housing means closing one end portion of said air tube; a second housing means closing an opposite end portion of said air tube; flame control means mounted on said first housing means and having a passage transverse to said tube for controlling a flame which is propagated transversely to the length of said tube through said passage in said flame control means; a hollow housing located in said first housing means and communicating with said passage in said flame control means, said hollow housing having a wall formed with at least one air passage therethrough; a nozzle extending transversely to said tube and being located in said hollow housing for directing a flame transversely to the length of said tube and through said passage in said flame control means; ignition electrode means also located in said hollow housing; leaf spring means connected to said hollow housing and engaging an inner surface portion of said first housing means, for urging said hollow housing into engagement with said flame control means; fuel supply means connected to said nozzle in said assembly and extending therefrom along the interior of said air tube towards said second housing means, said fuel supply means being removably connected to said second housing means and adapted to be connected with a source of fuel located outside of said second housing means; current supply means connected to said ignition electrode means in said hollow housing and extending therefrom along the interior of said air tube towards said second housing means and being removably connected to said second housing means; valve means located on said wall of said hollow housing for controlling flow of air through said air passage therein; operating means connected to said valve means for operating same and extending from said valve means through said tube to said second housing means and terminating outside of the same; and closure means in said second housing means opposite said opposite end portion of said air tube for closing and opening said second housing means for providing upon being opened, a 25 passage through which said hollow housing and assembly together with said fuel supply means and current supply means may be removed from and inserted into said air tube without disturbing the latter.

2. In a vertical flame oil burner, in combination, an elongated air tube; a first housing means mounted on said air tube for enclosing one end portion thereof; flame control means having a passage transverse to said tube and being mounted on said first housing means for controlling a flame propagated in a direction transverse to the length of said tube through said passage in said flame control means; a second housing means mounted on an opposite end portion of said tube, said second housing means having an end wall formed with an opening passing therethrough; a hollow housing located in said first housing means and communicating with said passage in said flame control means, said hollow housing having a bottom wall formed with an opening passing therethrough; a nozzle extending transverse to said tube and located in said hollow housing for directing a flame transversely to the length of said tube means and through said passage in said flame control means; a screw member passing through the bottom wall of said hollow housing being connected to said nozzle for fixing the latter in said hollow housing; a member turnably carried by said screw member at the exterior of said bottom wall for covering said opening therein to a selected extent to regulate the air flowing into said housing from the interior of said tube through said opening in said bottom wall; an elongated rod connected to said member and extending along the interior of said tube towards said end wall in said second housing means; means for adjustably fixing said rod to said second housing means so as to fix the position of said member; a pair of ignition electrodes also located in said hollow housing; a fuel supply duct communicating with said nozzle and extending through a wall of said hollow housing along the interior of said tube toward said end wall of said second housing means, said duct being removably connected to a portion of said second housing means adjacent said end wall and being adapted to communicate with a source of fuel at said portion of said second housing means; a pair of electrically conductive members extending from said electrodes, respectively, along the interior of said tube towards said end wall of said second housing means and being removably connected to said second housing means; and a closure plate connected to said end wall of said second housing means for covering and uncovering said opening in said end wall so that when said opening is uncovered, said hollow housing, with said nozzle and electrodes therein and together with said member, rod, fuel supply duct and pair of electrically conductive members may be inserted into or removed from said first housing means and the interior of said tube, respectively, through said opening in said end wall.
